UNITED STATES PATENT OFFICE.

FRANK T. STUART, OF MAPLEWOOD, NEW JERSEY, ASSIGNOR TO THE R. NEUMANN HARDWARE CO., A CORPORATION OF NEW JERSEY.

BAG FRAME.

Application filed July 10, 1926. Serial No. 121,616.

This invention relates to improvements in traveling bag frames; and the invention has reference, more particularly, to improvements in that type of bag-frame to which the bag-body is secured by sewing.

This invention has for its principal object to provide a novel construction of frame for "sewed-in" bags, which is provided with the usual adjuncts comprising a center lock, handle attachment loops, and end latches, and which is further provided with a novel construction and arrangement of frame interengaging and supporting elements, in association with said end latches, adapted to distribute the weight of the bag-body and its content substantially equally relative to both frame sections or members, so that sagging, distortion or other abnormal displacement of one frame member or section relative to the other is prevented.

Other objects of this invention, not at this time more particularly enumerated, will be clearly understood from the following description of the same.

The invention is clearly illustrated in the accompanying drawings, in which:—

Figure 1 is a side elevation of a bag-frame made according to and embodying the novel features of this invention; Figure 2 is an enlarged fragmentary longitudinal section of the same; Figure 3 is an enlarged bottom plan of the same; Figure 4 is a transverse section, taken on line 4—4 in Figure 2; and Figure 5 is a detail perspective of the interengageable supporting elements which are associated with the frame sections and end latches thereof.

Figure 6 is an enlarged fragmentary longitudinal section showing a modified form of frame section interengaging and supporting means; Figure 7 is an enlarged fragmentary bottom plan of the same; Figure 8 is a transverse section, taken on line 8—8 in Figure 6; and Figure 9 is a perspective of one of the novel supporting elements in said modified form.

Similar characters of reference are employed in all of the hereinabove described views, to indicate corresponding parts.

Referring now to said drawings, the reference characters 10 and 11 respectively indicate the outer and inner frame-sections, with which are respectively connected by brackets 12 and 13, their respective side-frame sections 14 and 15.

Centrally disposed in connection with the outer frame-section 10 is any desired form of center-lock 16 adapted to cooperate with locking elements (not shown) with which the inner frame-section 11 is provided.

Mounted on said outer frame-section 10, so as to be respectively spaced longitudinally from opposite ends of said center-lock 16 are any desired form of handle attachment loops 17.

Mounted on said outer frame-section 10, adjacent to each end thereof, are end latch or fastener devices. Each latch or fastener device comprises a suitably formed main body or shell 18 having in integral connection with its respective ends, so as to project downwardly therefrom and through perforations in the frame-section 10, provided for their reception, suitable clinching tongues or lugs 19. Pivotally connected with one end of said main body or shell 18 is a lever-plate 20 having at its free end an upwardly curved finger-piece 21. Said lever-plate 20 is so arranged that it normally lies along the top surface of said main body or shell 18, but is capable of being swung upwardly to substantially upright position. Arranged within said main body or shell 18 and cooperating with said lever-plate 20 so as to yieldably retain the same in either downfolded or up-raised position, in the usual manner familiar to those skilled in the art of bag-frame construction, is a leaf-spring 22. Secured to the underside of said lever-plate 20, so as to move therewith, is a suitably curved latch horn or finger 23. The top of said main body or shell and the underlying portion of said frame-section 10 are respectively provided with openings 24 and 25 to permit the normal projection of said latch horn or finger 23 downwardly therethrough.

Arranged beneath the outer frame section 10, in alignment with each latch or fastener device, is a supporting element adapted for interengagement with a combined cooperating supporting element and hasp-plate which is fixed to the inner frame section 11, so that when said frame sections are disposed in closed relation, not only is the inner frame section firmly sustained against vertical displacement or bending relative to the outer frame-section 10, and vice versa, but when the lever-plate 20 is down, a further cooperative relation is established between

said combined supporting element and hasp-plate with the lowered latch horn or finger 23 of the lever-plate, whereby said closed frame-sections are securely held at points 5 adjacent to their ends against undesired lateral separation. It is thus assured that both a secure closed relation of the bag frame-sections may be maintained, as well as an equal distribution of the weight of the 10 bag and its content relative to both frame-sections, to the end that upward bending or distortion of said outer frame-section 10 or downward bending or sagging of said inner frame-section 11, as the case may be, is effi- 15 ciently prevented.

In Figures 1 to 5 inclusive, I have shown one form of the novel cooperating frame supporting and closing elements made according to my present invention, the same 20 comprising a bridge plate 26 having at its extremities upwardly extending portions 27 from which project outwardly perforate abutments 28 to abut the under side of said outer frame section, with their perforations 25 matching the perforations of said frame section 10 through which the clinching lugs or tongues 19 of a latch or fastener device 18 extend. The bridge plate 26 thus constructed is downwardly off-set or spaced 30 from the under side of said outer frame section 10 to provide an intermediate receiving space 29. To secure the bridge plate 26 in the above described relation to the frame section 10 and latch or fastener device, the clinching lugs or tongues 19 of the latter are passed downwardly through the frame section and on through the perforate abutments 28 and then clinched over the latter, thus in a simple and economical manner firmly uniting and interrelating such parts. Said bridge plate 26 is provided 40 with a longitudinal slot 30 which is aligned with the openings 24 and 25 respectively of the latch device and frame section 10 to 45 permit the normal projection of the latch horn or finger 23 downwardly therethrough. The cooperating frame supporting and closing element, which is associated with the inner frame-section 11, comprises a combined bracket member and hasp-plate 50 consisting of a vertical portion 31 adapted to abut the outer surface of the side-frame section 15, to which it is firmly secured by a rivet 32 or other suitable fastening, and a 55 horizontal portion 33 adapted to abut the under surface of said inner frame section 11, to which it is firmly secured by a rivet 34 or other suitable fastening. Said vertical and 60 horizontal portions 31 and 33 are integrally connected by an inclined bracket portion 35 which extends across the space between said frame-section 11 and its side frame section 15, said bracket portion being cut away in its body to provide an opening 36 through 65 which the stitching connecting the bag-body

to the frame may be sewn. The free extremity of the horizontal portion 33 is provided with an extension forming a supporting tongue and hasp plate 37 which projects beyond the inner edge of said inner frame-section 11, to dispose the same for transverse alignment or opposition to the receiving space 29 intermediate the outer frame section 10 and the bridge plate 26, and consequently when the frame sections 70 are closed together, the combined supporting tongues and hasp plate at each end thereof will enter said receiving spaces above each bridge plate so that any tendency to vertical displacement or bending of either 75 frame-section is obstructed and prevented by the mutual engagement of said supporting tongues and bridge plates one with another. Before the frame sections can be closed together, the lever-plates 20 of the 80 latch devices must be swung upwardly to withdraw the latch horns or fingers 23. Each supporting tongue and hasp-plate 37 is provided in a side thereof with an indented slot or notch 38, which, when the supporting 85 tongues are entered above the bridge plates upon the closing together of the frame sections, will be aligned with the path of movement of the latch horns or fingers 23, so that as the lever plates 20 are swung down to 90 normal closed positions and said latch horns or fingers 23 project downwardly through the frame section 10 and bridge plates 26, the same will be caused to enter said slots or notches 38. Such interengagement of the 95 latch horns or fingers 23 with the combined supporting tongues and hasp plates 37 additionally serves to interlock the inner and outer frame sections at their respective ends in closed position, so that the same are held 100 at such points against accidental lateral separation or distortion, all in a manner clearly to be understood from an inspection of the accompanying drawings.

In Figures 6 to 9 inclusive, I have shown a modified form of my novel cooperating frame supporting and latching elements, which is, however, within the general scope of my present invention. This modified construction comprises a bridge-plate 39 having at its outer longitudinal edge a down-turned flange 40 to abut and be secured to the inner side of the side-frame section 14 of the outer frame 10, by means of rivets 41 or other suitable fastening means. The bridge plates 39 in such form are spaced beneath the outer frame-section 10, in alignment with the respective latch devices, to provide the intermediate receiving spaces 42. Said bridge plates 39 are provided with slots 43 to pass the latch horns of fasteners 23. The cooperating supporting elements attached to the inner frame-section 11 may be the same in structure as already 110 above described, or may be variously modified 115 120 125 130

fied to provide the combined slotted supporting tongues and hasp-plates adapted to enter the receiving spaces 42 above the bridge plates 39 so as to also receive and engage the latch horns or fingers of the latch devices, whereby both tendency to vertical displacement or distortion of the frame sections 10 and 11 as well as lateral opening or separation thereof is prevented in substantially the same manner as already above described.

Having thus described my present invention, I claim:—

In a bag-frame comprising an outer member and an inner member adapted to telescope into said outer member, latch devices mounted on said outer member adjacent to each end thereof, said latch devices having pivoted lever-plates provided with latch-horns depending therefrom and adapted to project downwardly through said outer member, bridge plates spaced beneath said outer member in alignment with said latch

devices, said bridge plates having at their ends upwardly off-set perforate abutments 25 to abut the under side of said outer member, said latch devices having at their ends clinching lugs to pass through said outer member and the perforate abutments of said bridge plates and adapted to be clinched 30 over to secure said parts together, and inwardly projecting combined supporting tongues and hasp-plates rigidly connected with said inner member in transverse alignment with said bridge plates, said combined supporting tongues and hasp-plates being adapted to engage over said bridge plates when said outer and inner member are closed together and at the same time being engageable by said latch horns to prevent lateral 40 separation or opening of said outer and inner members.

In testimony that I claim the invention set forth above I have hereunto set my hand this 6th day of July, 1926.

FRANK T. STUART.
